United States Patent Office

Des. 215,237

Patented Sept. 16, 1969

215,237

ELECTRIC IRON OR THE LIKE

Arthur E. Uber, Jr., Hampton Township, Allegheny County, Pa., Robert L. Finch, Mansfield, Ohio, and William A. English, Export, Pa., assignors to Westinghouse Electric Corporation, a corporation of Pennsylvania

Filed Mar. 20, 1967, Ser. No. 6,295

Term of patent 14 years

Int. Cl. D7—06

U.S. Cl. D49—6

FIG. 1

FIG. 2

FIG. 1 is a perspective view of an electric iron embodying our new design;

FIG. 2 is a side elevation view thereof.

The dominant features of our design reside in the portions shown in full lines.

FIG. 1 of the drawing is shaded to indicate contrast.

We claim:

The ornamental design for an electric iron or the like, as shown and described.
